UNITED STATES PATENT OFFICE.

CHESTER B. JOHNSON, OF HASBROUCK HEIGHTS, NEW JERSEY.

BEARER.

Application filed January 4, 1926. Serial No. 79,197.

The present invention relates to improvements in bearers for printing presses of the bed and cylinder type.

The invention is particularly concerned with improved means for securing the bearer to the press bed in such a manner that the bearer will offer a uniform wearing surface over which the cylinder travels.

It is customary to attach the bearers by inserting a number of screws through openings in the tops of the bearers. I have discovered that the edges of these screw holes become very rapidly worn down, and that the bearers frequently break or crack transversely at the points where they are weakened by the provision of the screw holes.

In order to overcome this difficulty, I employ a means for fastening the bearer which does not pass through its upper surface, and which will leave no screw hole openings in the face of the bearer over which the cylinder travels.

By virtue of my improved attaching means, I also render it possible to raise the bearers and insert packing therebeneath whenever occasion requires.

Further objects of the invention are to provide a bearer which may be rapidly installed or removed, which will be of simple, practical construction, which will be rugged, durable and highly efficient in use, and which may be manufactured with comparative economy.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a fragmentary plan view of the bed of a printing press showing my improved bearers in place, and supporting a type form between them.

Fig. 2 is a fragmentary edge view looking at the outside edge of one of the bearers.

Fig. 3 is a transverse sectional view on the line 3—3 of Fig. 1.

Fig. 4 is a cross-sectional view on the line 4—4 of Figure 1.

In the drawings I have used the reference character 10 to designate the bed of the press. A type form 11 is shown mounted in a type frame 12 by the use of suitable

quoins 13. The present invention is particularly concerned with the construction of the bearers 14 between which the type frame is mounted.

A feature of the present invention is the elimination of the usual screws which are passed directly through the top of the bearers and into the bed of the press. Instead of these screws, I use studs 21, fixed to the bed of the press as by screwing their lower ends into sockets in the press bed, the upper ends of which are threaded at 22 for the reception of clamping nuts 23. The outer lateral faces of the bearers are formed with approximately fan shaped recesses 24 therein, adapted to provide clearance for the free turning movement of the nuts 23. Recesses 24 are channelled out of the bearers and communicate with vertical recesses 25 receiving the shanks of the studs 21. By virtue of this construction, inwardly projecting lips 26 are formed under each clamping nut 23. In attaching the bearers to the bed of the press, the slots 25 are aligned with the studs 21, and the bearers slide laterally until the studs engage the bottom of these slots, at which time the clamping nuts 23 will be completely housed within the recesses 24. By tightening the clamping nuts 23 into firm engagement with the lips or flanges 26, the bearers will be securely locked against movement.

Obviously any suitable form of clamping nut might be utilized, but I prefer to use a nut having a number of radially disposed tool receiving pockets 27 in its periphery. The flaring or fan like shape of the slots 24 permits the nuts to be rotated through nearly a half turn at each insertion of a pin or other suitable tool into the pockets 27. In other words, the flaring shape of the slots is primarily to provide clearance for the movement of a nut operating tool.

From the foregoing description it will be evident that I have provided a bearer of much more rugged construction than the conventional type. By eliminating the screw holes in the upper face of the bearer, I prevent excessive wear at the edges of the holes where the cylinder travels over the bearer face. I also eliminate the tendency of the bearers to break at the points where they are held by their securing devices. I furthermore render the attachment or removal of the bearers to the press, extremely expeditious and simple. It will be obvious

that when it becomes desirable to elevate the bearers, such a result may be accomplished by merely loosening the nuts 23, inserting packing or shims under the bearers, 5 and subsequently retightening the nuts.

I prefer to associate with the bearers some type form locking means of the general character of that disclosed in my copending application Serial No. 69,896, filed November 18, 1925. The type form lock which I employ in the present instance however, is somewhat different than, and a considerable improvement on the type form locking mechanism of the above entitled application. 15 One of the principal features of improvement is the elimination of any slots in the upper surface of the bearer for the accommodation of the type form lock actuating means.

20 Each type form lock includes a flat clamping plate 18 carried at one end of a screw 17 working in a transverse threaded bore in the bearer. The ends of the screws are swivelly connected to the plates 18 as at 17^a, and closely adjacent the plates are integral or rigid with operating nuts or discs 16. The inner lateral faces of the bearers are provided with recesses 20 for accommodating the discs 16 and plates 18 when the screw 17 is moved to retract the plates out of engagement with the type frame 12. Each screw 17 is formed with a polygonal pocket 17^b in its other end, said pocket being adapted to receive a suitable turning tool for turning the 25 screws and projecting or retracting the locking plates 18. The nuts or discs 16 are formed with a polygonal series of radially disposed pockets 16^a for the reception of a turning tool. After the screw has been moved 30 a sufficient distance inwardly to project the nut 16 out of its recess 20, further tightening or projection may be effected by either manually grasping the nut and rotating it, or by inserting a handle pin into one of the 35 pockets 16^a. The plates 18 preferably carry guide pins 19 working in suitable recesses 19^a in the inner face of the bearer as described in my previous application. These guide pins assure movement of the locking plates 40 in planes parallel to the plane of the bearer, thereby facilitating proper angular adjustment of the type form relative to the bearers at all times.

Any suitable number of type form engaging mechanisms such as those just described 45 may be used with each bearer, and any other convenient or conventional type form engaging mechanism be substituted therefor. It is desirable that such mechanisms when used 50 shall be so arranged that it will be unnece-

sary to slot or aperture the upper surface of the bearer, whereby an uninterrupted uniform wearing surface is had.

The bearer which embodies both my improved type form clamping means, and the 65 improved securing means which forms the subject matter of the present invention, will be of course highly efficient from every angle, but it is to be understood that the present invention is applicable to all bearers regardless of whether or not they embody any type 70 form clamping means.

Various changes and alterations might be made in the general form and arrangement of parts described without departing from 75 the invention. Hence I do not wish to limit myself to the details set forth, but shall consider myself at liberty to make such changes and alterations as fairly fall within the spirit and scope of the appended claims.

I claim:

1. A bearer having recesses in its outer lateral face for the accommodation of clamping nuts, and vertical recesses communicating therewith for the accommodation of 85 securing studs, with which said nuts are adapted to coact.

2. The combination with a press bed and studs mounted in the bed, of a bearer having openings therein receiving the studs, 90 said openings terminating below the upper surface of the bearer and communicating with lateral recesses in the lateral face of the bearer adapted to receive clamping nuts for coaction with the studs.

3. The combination with a press bed and studs projecting upwardly therefrom, of clamping nuts on the upper ends of the studs, a bearer having vertical openings in its lower portion receiving the studs and 100 recesses in its lateral face receiving the nuts.

4. The combination with a press bed and studs projecting upwardly therefrom, of clamping nuts on the upper ends of the studs, a bearer having vertical openings in its lower portion receiving the studs and recesses in 105 its lateral face receiving the nuts, said recesses flaring at their mouths to facilitate turning of the clamping nuts.

5. The combination with a press bed and 110 studs projecting upwardly therefrom, of clamping nuts on the upper ends of the studs, a bearer having vertical openings in its lower portion receiving the studs and recesses in 115 its lateral face receiving the nuts, said openings communicating with the lateral surface of the bearer, whereby the bearer may be slid into position under the nuts.

CHESTER B. JOHNSON.
